UNITED STATES PATENT OFFICE

2,418,773

FUSE CHANGER

Henry J. Kahanek, Dallas, Tex.

Application September 9, 1944, Serial No. 553,444

3 Claims. (CL. 81—3.8)

1

This invention relates to article handling devices and it has particular reference to electrical fuse changers.

The principal object of the invention is to provide a simple device to facilitate the insertion and removal of fuses from fuse clamps in electrical systems. It frequently happens that the metallic ends of fuse plugs become so tightly wedged in their clamps as to make it impossible to effect their removal with the fingers and even when it is possible to so remove the fuse plugs, they are often dropped accidentally into the fuse box, sometimes causing short circuiting and are difficult to retrieve. The present invention provides a clamp with which is associated means having the dual effect of closing the clamp upon the fuse plug and of pulling the plug simultaneously.

Another object of the invention is to provide a fuse plug changing device consisting of a pair of hinged jaws, recessed to engage a fuse plug and spring actuated to normally grip the plug and through the jaws is threaded a cord in such a manner that any tension imposed on the cord will be transmitted to the jaws to constrain them to close about the plug with the force increasing in relation to the tension on the cord, so that a fuse plug may be displaced without subjecting the same to a crushing force.

Another object of the invention is to provide a fuse plug changing device which may be employed to insert a plug as efficiently as it is used for its removal and is so designed and constructed as to obviate any likelihood of current conductance.

With the foregoing objects as paramount, the invention has further reference to certain features of accomplishment which will become apparent as the description proceeds, taken in connection with the accompanying drawings where-

in:

Figure 1 is a perspective view of a fuse changing device constructed according to the present invention.

Figure 2 is a similar view, showing the clamp per se in longitudinal section.

Figure 3 is a plan view of one section of the clamp, the companion section having been removed to better illustrate the manner in which the pull cord is threaded through the clamp.

Figure 4 is a transverse section taken on line 4—4 on Figure 2 and,

Figure 5 is a side elevational view of the clamp expanded.

Continuing with a more detailed description of 55 It is obvious that the constricting force is in

2

the drawing, reference numerals 10 and 11 denote the two sections of the clamp which are constructed preferably from wood or plastic but may obviously be produced from any nonconductive material. The clamp elements 10 and 11, which may be hereinafter referred to as jaws, are held in pivotal relationship by means of a coil spring 12, one end of the latter extending forwardly and entering an opening intermediate the ends of the jaw 11 while the other end extends in intercrossing relationship to enter a transverse opening through the companion jaw 10, the main body portion of the spring reposing in joint recesses 13 and 14 in the jaws 10 and 11 respectively. In order to insure adequate displacement of the jaws 10 and 11, the spring 12 is disposed nearer to the handle end of the clamp. At the operative end of the clamp, confronting circular recesses 15 and 16 are provided which are adapted to embrace a fuse plug but are preferably of such size as to provide a clearance between the jaws and the fuse plug so that the latter will not be subjected to a force likely to crush the same as it is being pulled from its clamp.

Obviously, the spring 12 is effective to maintain normal closed position of the jaws 10 and 11 but to supplement the pressure supplied by the spring, a stout cord 17 is passed through the convolutions of the spring 12, thence through an oblique opening 18 in the jaw 11; along the outer face of this jaw, thence through axially aligned openings 19 in both jaws 10 and 11; thence along the outer face of the companion jaw 10 to an oblique opening 20, corresponding to the oblique opening 18, thence rearwardly through the convolutions of the spring 12 and between the two jaws 10 and 11 parallel with the companion lead of the cord. The ends of the cord have attached thereto a knob 21 for convenience in pulling the cord.

From the foregoing it is apparent that when the handle ends of the jaw members 10 and 11 are pressed together by the thumb and finger, resistance of the spring 12 is overcome and the recessed ends of the jaws are expanded so that they may be clamped upon a fuse plug. When this is done, the ends of the jaws are released and the spring will hold the clamp on the fuse plug. A pull is exerted upon the cord 17, better results being obtained by a quick jerk. The tension thus imposed upon the cord will be transmitted beyond the pivotal point of the jaws to exert counter pressures at the operative ends of the jaws to constrict the latter on the fuse plug.

direct relation to the tension imposed upon the cord 17, hence it is entirely unlikely that the jaws will slip over the fuse plug but will be effective to pull the latter from its clamp without fracturing the same.

In inserting a fuse plug in its socket or clamp, the jaws 10 and 11 are displaced sufficiently to engage a fuse plug and by which the latter is thrust in place. Should the jaws have a tendency to move apart under the pressure required to insert the fuse plug, the cord 17 may be pulled at the same time that the clamp is advanced to insert the plug. In this manner the jaws of the clamp may be tightly contracted onto the fuse plug to prevent displacement thereof.

It is apparent that the herein described clamp may find many other uses than the insertion and removal of fuse plugs and it is not intended that the same be so limited. It is also apparent that certain changes and modifications in construction may be resorted to from time to time without departing from the spirit and intent of the invention as fall within the meaning and scope of the appended claims therefor.

What is claimed is:

1. A fuse changing device including a pair of pivoted jaws, normally closed under spring tension and having complementary fuse engaging recesses at one end, a cord passing from one jaw to the other through spaced apart openings in each jaw and extending between said apertures on the outside of said jaws, defining a loop interconnecting said jaws thence extending rearwardly between said jaws and adapted, when pulled, to exert a closing force on said jaws.

2. A fuse plug changer including a clamp consisting of relatively pivoted jaws having spaced

apart apertures therein and held normally closed under spring tension and further having corresponding fuse engaging recesses at their operative ends, and flexible means looped through the

5 apertures in each of said jaws and passing from one jaw to the other and between the apertures on the outside of each jaw and extending rearwardly thereof therebetween for imposing a closing force on said jaws when a pull is exerted thereon.

10 3. A fuse changer including a pair of relatively hinged jaws held normally in closed position under spring tension and having corresponding fuse engaging recesses in their ends, and a cord 15 looped through apertures adjacent the end of each jaw to extend from one jaw to the other through said apertures, thence extending rearwardly between said jaws and adapted, under tension, to urge said jaws operatively together.
